UNITED STATES PATENT OFFICE

115,290

DESIGN FOR A VASE OR SIMILAR ARTICLE

Sydney Eustace Hill, Witton, Birmingham, England, assignor to Pearson-Page-Jewsbury Co. Limited, Witton, Birmingham, England, a British company

Application April 7, 1939, Serial No. 84,104
In Great Britain March 17, 1939

Term of patent 7 years

To all whom it may concern:

Be it known that I, Sydney Eustace Hill, a subject of the King of Great Britain, residing at Westwood Works, Westwood Road, Witton, Birmingham, 6, England, have invented a new, original, and ornamental Design for a Vase or Similar Article, of which the following is a specification, reference being had to the accompanying drawing, forming part thereof.

Fig. 1 is a front elevational view of a vase showing my new design.

Fig. 2 is a rear elevational view thereof.

Fig. 3 is a top plan view.

Fig. 4 is a side elevational view.

I claim:

The ornamental design for a vase or similar article, as shown.

SYDNEY EUSTACE HILL.
